UNITED STATES PATENT OFFICE.

WILLIAM PARFREY, OF NEW YORK, N. Y.

INCANDESCENT BURNER.

SPECIFICATION forming part of Letters Patent No. 733,746, dated September 8, 1903.

Application filed January 15, 1902. Serial No. 29,851. (No model.)

To all whom it may concern:

Be it known that I, WILLIAM PARFREY, a subject of the King of Great Britain, residing at New York, in the county and State of New York, have invented a new and useful Incandescent Burner, of which the following is a specification.

My invention relates to improvements in incandescent-light burners; and the object thereof is to provide means for heating the air before mixing it with the gas, another object being to regulate the flow of air to the heating-chamber, and a further object being to regulate the flow of air and gas and the distribution of the same at the burner. I attain these objects by the construction illustrated in the accompanying drawings, in which—

Figure 1 is a vertical section of an incandescent burner constructed according to one form of my invention, a part of the mantle being shown in connection therewith. Fig. 2 is a view similar to Fig. 1, but showing a number of modifications in the details of construction. Fig. 3 is an enlarged vertical section of one form of gas regulator or check. Fig. 4 is a vertical section, enlarged, of another form of gas regulator or check; and Fig. 5 is a bottom plan view of one of the tubes shown in Fig. 2.

In the accompanying drawings the several parts of my invention are indicated by numerals of reference, and in the practice of my invention I provide a tube 6, similar in form and construction to any tube used in a Bunsen burner and having the usual air-inlets 7, which may be closed or partially closed by a slide 8, operated by a rod 9 and having a gas-tip 10, mounted in a socket 11, which is secured within the lower end thereof. Mounted on the top of the tube 6 is a discharge-nozzle comprising an expansion-chamber 12, in the top of which is mounted the usual wire-gauze 13, surrounding which is the mantle 14, held by a support 15. Immediately beneath the chamber 12 and separated therefrom by a partition 16 is an enlarged heating-chamber 17, which is in communication with the a nosphere through a tube 18. I also provide a chamber 19, sur-

rounding the air-inlets 7 and in communication with the chamber 17 through a short tube 20.

The operation is as follows: Gas is admitted to the burner through the tip 10, having a discharge-opening proportioned in size according to the quantity of gas to be consumed. Air is admitted to the chamber 17 through the tube 18, and as this is beneath and near the flame the air will become heated to 60 quite a high degree before passing through the tube 20 to the chamber 19, from which it will pass into the tube 6 through the opening 7 and will become mixed with the gas before passing through the gauze 13 to be 65 consumed. I have found in practice that by heating the air before mixing it with the gas and then passing the air and gas through the heating-chamber the gas will expand, thereby retarding the flow to a certain extent, and when the gas and air are discharged within the mantle a higher degree of incandescence can be secured than where the air is introduced without previously heating it.

In the form shown in Fig. 1 the flow of air 75 is regulated by the slide 8; but I prefer to regulate the flow of air by a damper 21, mounted in the lower end of the tube 18, so that only the amount of air required is admitted to the heating-chamber and is not drawn 80 therefrom until needed to mix with the gas.

The gas-regulator shown in Figs. 1 and 3 comprises a conical-shaped tip 10, held in the socket 11 by friction, and may be readily removed and a tip having a different-sized aperture may be inserted, as will be readily understood, according to the quantity of gas to be consumed.

In Fig. 4 I have shown a gas-regulator comprising a thimble-shaped piece 11', having a plurality of apertures 22; but in regulating the flow of gas with a regulator of this kind the entire piece must be replaced, while with the regulator shown in Fig. 3 only the tip need be changed.

While my apparatus and system of heating the air and gas before consumption may be used in connection with the ordinary wire-gauze discharge-nozzle, as described in connection with Fig. 1, I prefer to use the nozzle 13'. 95

(Shown in Fig. 2.) This tip is thimble-shaped in form, having a semispherical end 23, in which are a plurality of perforations 24 sufficient in number and so disposed that the gas 5 will be discharged within the mantle at the sides of the nozzle, as well as at the top thereof, thereby distributing the flame more evenly over the mantle and especially at the base thereof. When this nozzle is used, it is made 10 of sufficient size so that the base will serve as an expansion-chamber instead of having to provide an expansion-chamber, as 12 in Fig. 1.

It will thus be seen that I have provided a 15 very efficient incandescent burner in a simple and inexpensive manner. By actual use I have found that I can save a considerable percentage of the gas required with the incandescent burners in common use.

20 It is evident that many changes may be made in the details of construction without departing from the spirit of my invention, such as changing the form of damper in the tube 18' or in substituting any well-known 25 means for controlling the admission of air to the chamber 6, and I reserve the right to make such changes.

Having thus described my invention, what I claim as new, and desire to secure by Letters 30 Patent, is—

1. An incandescent burner comprising a heating-chamber; means for admitting air thereto; a burner-tube; means to convey heated air from said chamber to said burner- 35 tube; means to admit gas to said tube, and a discharge-nozzle mounted above said burner-tube, said heating-chamber being located be-

neath said nozzle, as and for the purpose set forth.

2. An incandescent burner comprising a 40 heating-chamber, a tube to admit air to said chamber; means to control the admission of air through said tube; means to convey the heated air from said chamber to the burner-tube; means to admit gas to said burner-tube; and a discharge-nozzle mounted above 45 said burner-tube and heating-chamber, as and for the purpose set forth.

3. An incandescent burner comprising a heating-chamber; a tube to admit air thereto; 50 a damper mounted in said tube; means to convey the heated air to the burner-tube; means to admit gas to said burner-tube; and a discharge-nozzle mounted above said burner-tube and heating-chamber, as and for the 55 purpose set forth.

4. An incandescent burner comprising a heating-chamber; means for admitting air thereto; a burner-tube; means to convey the heated air from said chamber to said burner-tube; means to admit gas to said tube, and a thimble-shaped discharge-nozzle mounted above 60 said burner-tube having a semispherical end with perforations in the top and sides thereof, said heating-chamber being located 65 beneath said nozzle, as and for the purpose set forth.

In testimony whereof I have signed my name to this specification in the presence of two subscribing witnesses.

WILLIAM PARFREY.
